UNITED STATES PATENT OFFICE

HARLOWE HARDINGE, OF YORK, PENNSYLVANIA, ASSIGNOR TO HARDINGE COMPANY, INCORPORATED, OF YORK, PENNSYLVANIA, A CORPORATION OF NEW YORK

GRINDING MILL

Application filed July 22, 1929. Serial No. 379,897.

This invention relates to grinding mills, and more particularly to discharge means therefor.

One of the objects of the invention is to provide discharge means at the discharge end of a grinding mill which will operate to strain the pulp carrying pulverized material from the mill and permit the same to pass out of the mill, while at the same time operating to return balls and oversize material which comes in contact therewith.

Another object of the invention is to provide discharge means in the form of vanes which are carried by the mill during its rotation and which are so constructed as to enable the use of relatively fine screens without injury thereto and without clogging of meshes thereof because of the action of balls or coarse material likely to come into contact therewith.

Another object of the invention is to provide discharge means offering substantially no restriction to the flow of material from the grinding zone to the discharge end of the mill.

Another object of the invention is to provide discharge means having vanes of screening material which are so formed as to be self-cleaning.

Other objects and advantages will be pointed out hereinafter in the description and in the claims appended thereto.

In the drawings,

Fig. 1 illustrates a grinding mill in conjunction with a discharge device embodying my invention.

Fig. 2 is an end view of the discharge device of Fig. 1, taken on line 2—2 of Fig. 1.

Fig. 3 is a section through the discharge means, on line 3—3 of Fig. 1.

Fig. 4 is a perspective view of a portion of a mill with the discharge device.

Referring to Fig. 1, the invention is illustrated in conjunction with a well known type of mill, although it is to be understood that the invention has utility with other types of grinding mills.

As is well understood, the mill illustrated is adapted to be supported for rotation on trunnions 10, 11, which are hollow and through

which material may pass. The scoop feeder 12 serves to feed material into the mill through trunnion 10, and the material, pulverized to the desired fineness, passes out with the water or other liquid used in the grinding process at the discharge end 13. The mill illustrated has a conical discharge portion 14 and, as is well understood, different sizes of material being ground within the mill and the grinding media assume positions within this conical portion 14 in accordance with their relative sizes. That is, as the mill rotates, the larger particles become located in the vicinity of the cylindrical portion 15 of the mill, and the remaining material classifies itself according to size, with the finer particles thereof graded toward and located at the discharge end of the mill. While mills of this type need not necessarily be provided with discharge means of the character about to be described, it has become the practice to operate grinding mills under overload conditions, with the result that coarse material (and sometimes balls) is likely to be discharged at the discharge end of the mill, and therefore, under these circumstances, it becomes desirable to use discharge means which will prevent the discharge of coarse material and grinding media.

The discharge means of my invention comprises a plurality of vanes 16, having their outer edges in contact with the shell of the mill and extending toward the center line of the mill. I prefer to curve the vanes in the manner illustrated in Fig. 2, but it is obvious that these vanes may take other forms, such as in a radial plane or in a plane not intersecting the center line of the mill.

Referring to Fig. 1, the discharge means is so constructed as to function in a clockwise direction as viewed from the right. The vanes are made of screen material of such mesh, or of crossed wires so spaced, as to insure the separation of material of a coarseness greater than that desired as a product. The screening material 17 of each vane is secured to one side of a grille 18 which in turn is mounted in place by means of bolts 19, 20 and 21, Fig. 1. The spacing of the bars of the grille is such as to protect the small perforations of the screen-

- ing material from the impact of the balls and of coarse material. As the mill is rotated these bars come in contact with material which has come from the grinding zone including 6 any balls which may have happened to have dropped within the area occupied by the discharge means.
- Since grille 18 of each vane is on the surface of a vane which faces upwardly when rising as 10 the mill rotates, the grille 18 will save harmless the relatively fine meshes of the screen 17 from the action of balls or coarse material which might come within the area occupied by the discharge device.
- 13 The vanes 16 are set substantially parallel to the flow of material outgoing from the mill, thereby affording substantially no restriction or interruption of the free flow of material out of the mill.
- 20 They are further characterized by their curved surfaces which have their concave sides facing upwardly as they rise when the mill rotates. The outer edge of each vane is in contact with the inner wall of the drum 25 and, by virtue of the curved form of each vane, a scooping action is produced as it passes through material. This results in producing a partial cross-flow of material over the surface of a vane which tends to clean the 30 meshes of the screen. A vane formed in the manner described utilizes its screen area to the best advantage as the scooping action allows the fines to drain off above the water level from portions of the screen which successively pass through a horizontal position. 35 Therefore, a small grate area used in this manner can do many times the work the same grate area could do if it were located below the surface of the material or liquid being screened.
- In order to permit overloading conditions in a mill of the character described, I provide 40 a wall 22 which, in the embodiment of the invention illustrated, is in the form of a conical surface positioned reversely in respect to the discharge conical portion 14 of the mill. Wall 22 may be made of one piece, or may be made of a plurality of sections 23, as illustrated in Fig. 2, and, in any event, it may be 45 secured to the shell of the mill by means of bolts 20.
- Wall 22 is provided with a central opening 24 through which material and water within the mill may flow in its progress 50 from the mill. In cases in which it is desired to maintain a low pulp line, additional ports such as ports 25 may be provided, in any number and size. When the mill is operating under overload conditions, it will 55 be appreciated that balls or coarse material are likely to pass through opening 24 and come into contact with the discharge means just described. When such event occurs, such balls and material might be discharged 60 from the mill if proper provision has not been made to return them to the grinding zone of the mill. In the present instance these balls and coarse material strike upon the grille 18, and, as the mill is rotated, they are scooped up into troughs 26, one of which 70 is provided for each vane 16. These troughs are so sloped that when they have been rotated to a horizontal position the coarse material will start to gravitate toward the opening 24 of wall 22. The momentum of 75 the coarse material, and particularly of the balls, caused by the inclination which the troughs assume at or near their highest position of travel, is sufficient to cause the balls to be carried well backward into the grinding zone.
- It will be noted that there is a clear passage straight through the mill, with the result that there is no impediment to the free flow of material through the zone of the 80 discharge means except to the extent which may be charged to the agitation and screening effect of the vanes themselves. Advantage is taken of the fact that the rate of flow through the zone of the discharge 85 means is slower than the rate at which the vanes rotate, and therefore practically no material can pass out of the mill without having been subjected to the screening effect of the discharge means unless under exceedingly high overload conditions, under which 90 conditions the rate of travel through the mill or through the zone of the discharge means is in excess of the rate at which the vanes move as the mill is rotated. Under 95 this latter condition oversize material may be discharged, but this is an advantage since the discharge of oversize material constitutes a signal to an operator that the mill is overloaded beyond the point at which it can be 100 grinding satisfactorily.
- While I have, in many instances, in the 105 description of my invention and in the claims, referred to balls as one form of grinding media, I wish it to be understood 110 that I intend such reference to designate any kind of grinding media whatsoever, as, for example, balls, pebbles, bars, disks and kindred shapes of suitable material.
- I claim:
1. In a grinding mill, the combination 115 with a rotary drum, of a discharge device therein having vanes comprising perforated material, and a wall separating the discharge device from the grinding zone of the mill, said wall being conical with its convex surface facing the grinding zone of the mill.
2. In a grinding mill, the combination 120 with a rotary drum having a conical portion with its small end toward the discharge end of the mill, of a discharge device therein having vanes comprising perforated material, a wall separating the discharge device from the grinding zone of the mill, said wall having an opening at its midpoint per-

mitting the flow of material from the grinding zone of the mill to the discharge device, and means for receiving coarse material and balls from said vanes which has passed 5 through said opening from the grinding zone.

3. The combination set forth in claim 2 in which the means for receiving coarse material and balls from the vanes comprises 10 troughs, one of which is associated with the inner edge of each vane.

4. In a grinding mill, the combination with a rotary drum, of a discharge device therein having vanes comprising perforated 15 material, a wall separating the discharge device from the grinding zone of the mill, said wall having an opening at its midpoint permitting the flow of material from the grinding zone of the mill to the discharge 20 device, and troughs at the inner edges of said vanes, one of said troughs being provided for each of said vanes and having one side in continuation of its associated vane and another side sloping in respect to the 25 axis of the mill so as to return oversize material and balls to the grinding zone as the trough rises during the rotation of the mill.

5. In a grinding mill, the combination with a rotary drum, of a discharge device located 30 at the discharge end of the mill and having perforated vanes for screening material coming into contact therewith, each of said vanes being mounted to rotate with the mill and formed so that substantially all portions 35 of its surface leave the flow of material with the outer surface extending upwardly at an angle to the surface of the material flowing from the grinding zone to the discharge end of the mill.

40 6. In a grinding mill, the combination with a rotary drum, of a discharge device through which material flows to the discharge end of the mill and having perforated vanes for screening material coming into contact therewith, said vanes being concave with the concave surface thereof facing upwardly when rising as the drum rotates and extending a direction lengthwise of the mill which is substantially longitudinal of the flow of material 45 by the discharge device.

7. In a grinding mill, the combination with a rotary drum, of a discharge device located at the discharge end of the mill and having perforated vanes for screening material 55 coming into contact therewith, said vanes comprising screening and a grille on the side of the screening which faces upwardly when rising as the drum rotates.

60 8. In a grinding mill, the combination of a rotary drum and screening means having a perforated device for screening material to be discharged from the mill, said device comprising a curved vane mounted to rotate 65 with the mill, the surface of the vane which

extends toward the axis of rotation, being substantially radial with the axis of rotation and the end furthest away from the axis of rotation and adjacent the wall of the mill being curved, whereby material, with the exception of oversize pieces, may freely flow from the grinding zone of the mill and be discharged from the mill, and means for returning the oversize pieces to the grinding zone of the mill. 70 75

9. In a grinding mill, the combination of a rotary drum and screening means having a perforated device for screening material to be discharged from the mill, said perforated device comprising a vane extending inwardly from the wall of the mill, a wall separating the screening device from the grinding zone of the mill, and means for receiving oversize pieces of material from said perforated device as the mill is rotated and for directing the oversize pieces through the opening in the separating wall. 80 85

10. In a grinding mill, the combination of a rotary drum having a conical discharge end open at its small end, a discharge device located within the conical discharge end, said discharge device comprising a perforated vane having perforations therein for screening material leaving the mill, the surface of said vane being curved, a wall separating the discharge device from the grinding zone of the mill and protecting the perforated vane, said wall having openings for the passage of material, and means bordering the inner line of said vane for receiving 90 95 material from the vane and for directing the same through one of said openings to the grinding zone of the mill. 100

11. In combination, a rotary grinding mill through which material advances along the 105 axis of the mill as it is being comminuted, and a screening device interposed in the path of travel of the material leaving the grinding zone of the mill, said screening device comprising a plurality of perforated members 110 extending lengthwise of the mill and from the wall of the mill toward its axis but leaving space at opposite sides and at the free edges of the perforated members, said space forming unobstructed passageways 115 through the screening device through which material may pass the screening device without being screened.

12. In combination, a rotary grinding mill having an inlet opening at one end and 120 a discharge opening at its other end and through which material advances as it is being comminuted, a screening device at its discharge end comprising at least one perforated member extending lengthwise of the 125 mill and from the wall of the mill toward the axis but terminating short thereof, and a perforated wall between the grinding zone of the mill and the screening device so that the entrance of material to the screening de- 130

- vice is restricted, whereby some of the material flowing through the zone of the screening device may be screened and some of the material may pass to the outlet of the mill without passing through the perforations in the perforated member.
13. In combination, a rotary grinding mill through which material advances to an outlet at one end of the mill, a screening device in the path of the material advancing to the outlet, said screening device comprising a plurality of perforated members extending longitudinally of the mill and having their outer edges attached to the wall of the mill but circumferentially spaced from each other, the inner edges of the perforated members being spaced from each other to permit the free flow of material through the spaces between the successive perforated members,
18. a perforated wall separating the screening device from the grinding zone of the mill, and means for returning to the grinding zone of the mill substances picked up by said screening device.
23. In testimony whereof I hereto affix my signature.

HARLOWE HARDINGE.
